John D. Sherman INVENTOR.

BY

Accent Allen ATTORNEYS.

UNITED STATES PATENT OFFICE.

JOHN Q. SHERMAN, OF DAYTON, OHIO.

MANIFOLDING REGISTER.

Application filed January 20, 1923. Serial No. 613,843.

My invention relates to manifolding registers which are combined with cash drawer mounting and projecting devices, and has as its object the use of the force required to close the cash drawer in operating paper feed devices to issue manifolding forms.

The cash drawer type of manifolding device is becoming widely used because of the convenience of associating together the issuing of a sales slip by the same clerk who makes change or places money in the cash drawer. The enforcement of a feed of paper through the manifolder every time the drawer is opened, is also an excellent check on the transactions made during any period of operation.

By storing up energy during the closing of the cash drawer which energy is used for the operation of paper feed devices, the number of operations necessary in completing any one transaction are cut down over machines of which I have knowledge, and in a properly safeguarded construction insure the issuance of a slip every time the drawer is operated since no exposed part is necessarily available to the operator for controlling the paper feed.

While I desire to include in my invention any way of using the cash drawer to operate the paper feed, it is one of my special objects in the preferred construction illustrated herein, to use the cash drawer to set a spring, and then to release the spring for a steady and controlled operation of a paper feed.

Another special object of my invention is to provide for an operating button or the like, which when depressed will release the cash drawer, and paper feed device, and in which the maintenance of the button in closed position will not permit the operator to grasp the paper in his hand and withdraw more than the amount regularly fed by the feeding mechanism.

These objects and other advantages to be noted I accomplish by that certain construction and arrangement of parts to be herein after more specifically pointed out and claimed.

In the drawings:

Figure 1 is a side elevation of a machine showing my device, the housing parts being removed so as to expose the mechanism.

Figure 2 is a detail section on the line 2-2 of Fig. 1, showing the operating parts for driving the chain.

Figure 3 is a detail side elevation showing the rack and the end of the feed operating slide.

Figure 4 is a detail showing the ratchet drive for the chain sprocket.

Figure 5 is a detail side elevation showing the push button trip device for releasing the feed and the cash drawer.

Figure 6 is a detail front elevation of the feed shaft and its connection.

Figure 7 is a side elevation detail of the feed stop and trip device.

Referring to the special form of mechanism shown, the device has a cabinet 1, within which is supported in any desired manner a cash drawer 2. This drawer has a spiral spring 3 thereon which engages a cup 4 on the base of the cabinet, this device serving to project the drawer suddenly when the latch therefor is released.

The manifolding register parts shown include a frame 5, within which are spindles 6 for the paper rolls 7. The paper passes over a suitable support to serve as a writing surface, and is fed by means of pin wheels 8, engaging apertures in the paper, preferably along the two margins thereof. The United States patent to Schirmer No. 940,481, dated Nov. 16, 1909, is referred to as describing a pin wheel feed.

The pin wheels are mounted on a shaft 9, with which they revolve, this shaft having a sprocket thereon, as at 10, which is driven by a chain 11. The chain 11 passes over a vertical roller 12, suitably supported between the sides of the frame, and over a driving sprocket 13 mounted on a shaft 14. The advantage of using the pin wheel paper feed with my device is that it insures a positive quantity of paper being fed at each operation. It also results in a true alignment of webs, and its nature which insures equal amount of feed for all paper webs at all times, permits of the use of automatic feeding mechanisms, which are normally locked up.

Mounted within the frame and extending about half the length thereof are a pair of spaced rods 15, and at the forward end of the machine is arranged a long dash pot 16, lying preferably between the lines as if extended which are formed by the rods. To mount the rods they are set into socket pieces 17 at the rear wall of the device, and mounted in castings 18, near the center of the machine. These castings will be mounted

ed on the sides of the frame, and will also have sockets to receive the shaft 14.

Mounted to slide on the spaced rods is a plate 19 having sleeves 20 mounted over the rods. This plate has also ears 21 which are secured to long springs 21^a, which extend to the front of the machine.

The dash pot will be mounted in any desired manner, as for example by ears (not shown) at the front of the machine. The plate 19 has a rod 22 secured thereto, said rod being cut with rack teeth 23, and carrying at its forward end a disk 24 which lies in the dash pot where it acts like a piston.

The plate 19 has a depending tongue 25 which lies in a position to be engaged by the back wall of the cash drawer, thus when the cash drawer is pushed in, the plate will be moved inwardly, extending the long springs. Then when the drawer is released the plate will be pulled forwardly, being retarded by the dash pot.

The rack 23 will engage a gear 23^a on the shaft 14, which gear is loose thereon and drives the shaft by means of a pawl 25^a engaging the ratchet 26, that is fast on the shaft. This insures a driving of the shaft 14 in one direction only, which will so rotate the chain sprocket 13 thereon as to feed the paper out of the machine.

To control the amount of paper fed at each operation, I fix upon the feed shaft a cam disk 27, the nose of which contacts with the end of a centrally pivoted lever 28. This lever has a stud 29 on it, and is held against the cam by a spring 30. The stud will be engaged by another lever, 31, severing as a latch and having a notch 32 for engaging the stud. This lever springs up to engage the said stud by force of the spring 33, and is tripped to release the stud by means of a pin 34 on the cam.

The devices for releasing the drawer and for tripping the latch lever for the feed shaft, are shown as formed of a long bar 40 held loosely in brackets 41 along the side of the machine. The inner end of this bar is coupled by means of a link 42, with a cross shaft 43. The shaft 43 carries a hook 44, which engages the rear end of the drawer. If desired a spring 45 may be used with this hook, and also a spring 46 is coupled to the long bar, which spring acts in the same direction.

On the long bar is a sloping tooth 47, which when the bar is pushed in, as by a contact plunger 48, will move the end of the latch lever over until it releases the cam on the feed shaft by riding out from under the nose thereon, and being held out by the additional latch lever.

This release of the feed will take place, preferably, just prior to complete release of the cash drawer, with the result that any re-

lease of the cash drawer must be accompanied by a feeding of the paper.

The maintenance of the plunger 48 in its inward position will not serve to prevent the feed shaft from being stopped by the cam and lever. Thus the feed shaft will be revolved by the rack being pulled slowly forward and thereby operating the sprocket chain. As soon as a partial movement of the feed shaft has taken place the latch lever will be released by the pin on the cam knocking up the additional latch piece. The latch lever will then follow the cam under the force of its spring. The sliding bar that operates the trip is free to pass under the end of the latch lever, since it is loosely mounted and can tilt in its mounting brackets.

It is not desired, because of a mention of but a single set of mechanisms to operate in the manner described of energizing the feed from the manually operated movement of the cash drawer, to limit my invention to this particular means alone, since I desire to cover in this invention any form of mechanism embodying the principles of the devices described above.

Having thus described my invention what I claim as new and desire to secure by Letters Patent is:—

1. In a manifolding device including a cash drawer, a cabinet, cash drawer, and paper feeding mechanism, a latch for the paper feeding mechanism releasing it for definite operations at each operation of the latch, and a latch for the cash drawer, common means for operating said latches, and means for actuating the feeding mechanism by the movement of the cash drawer.

2. In a manifolding device including a cash drawer, a cabinet, cash drawer, and paper feeding mechanism, a latch for the paper feeding mechanism releasing it for definite operations at each operation of the latch, and a latch for the cash drawer, common means for operating said latches, and means for actuating the feeding mechanism by the movement of the cash drawer, said means including a spring set under tension by the inward or closing movement of the cash drawer.

3. In a manifolding device including a cash drawer, the combination of a paper feeding device, a movable cash drawer, and mechanism energized by the closing movement of the cash drawer, to operate the feeding devices, and a latch for the feeding device adapted to permit but one predetermined operation of the feed device upon each movement of the cash drawer, and an operating device for the latch, said operating device adapted to trip the latch, at each actuation thereof.

4. In a device of the character described, the combination of a paper feeding device,

- a cash drawer and a cabinet therefor, a movable rack having driving connection with the paper feeding device, means on the rack lying in the path of the cash drawer, spring 5 means setting the rack under pressure when the drawer is moved inwardly to closing position, a latch for the drawer, and a stop for the feeding mechanism releasing it for definite operations at each operation of the 10 latch, and means for releasing said latch and stop.
5. In a device of the character described, the combination of a paper feeding device, a cash drawer and a cabinet therefor, a movable 15 rack having driving connection with the paper feeding device, means on the rack lying in the path of the cash drawer, spring means setting the rack under pressure when the drawer is moved inwardly to closing position, a latch for the drawer, and a stop for the feeding mechanism releasing it for definite operations at each operation of the latch, and means for releasing said latch and stop, 20 said means being adapted to first release the paper feed and then release the cash drawer 25
6. In a manifolding device including a paper feeding mechanism, a cabinet and a cash drawer in the cabinet, a power device for operating the feeding mechanism comprising a rack and spring, means on the cash drawer 30 to energize said power device upon the closing movement of the drawer, and means as a dash pot for retarding the movement of the feeding mechanism independent of the movement of the drawer. 35
7. In a manifolding device including a paper feeding mechanism, a cabinet and a cash drawer in the cabinet; a power device for operating the feeding mechanism, means on the cash drawer to energize said power device upon the closing movement of the drawer, and means for retarding the movement of the feeding mechanism independent of the movement of the drawer, a paper feed stop for controlling the operation of the 40 feeding mechanism, and a drawer latch, and means for operating said devices in desired sequence. 45

JOHN Q. SHERMAN.
